UNITED STATES PATENT OFFICE.

ALBERT D. CROSSLEY, OF HARTFORD, CONNECTICUT, ASSIGNOR OF ONE-FOURTH TO JOHN J. HARTY, OF KINGSTON, ONTARIO, CANADA, AND ONE-FOURTH TO WILLIAM P. O'BRIEN, OF MONTREAL, QUEBEC, CANADA.

FIRE-LADDER TRUCK.

1,076,104.

Specification of Letters Patent.

Patented Oct. 21, 1913.

Application filed March 17, 1913. Serial No. 754,911.

To all whom it may concern:

Be it known that I, ALBERT D. CROSSLEY, a citizen of the United States, residing at Hartford, in the county of Hartford and State of Connecticut, have invented a new and useful Improvement in Fire-Ladder Trucks, of which the following is a specification.

This invention relates to an apparatus which is designed to carry a number of ladders for the use of firemen.

The object of the invention is to provide a simple and strong truck of this character which will carry a number of ladders arranged in berths in such manner that any particular one of them which is desired for use can be easily and quickly removed without disturbing the others.

The invention is illustrated as embodied in a motor driven truck. Upon the truck frame are central supports which have cross arms that extend transversely at different levels for holding the ladders. These cross arms provide ladder berths that are unobstructed on each side so that the ladders can be removed from the berths without being pulled out lengthwise. On the arms are carriages for the immediate support of the ladders. The carriages on the same side of the center and at the same level are connected and can be moved out or in by means of a bar at the front end of the truck for bringing out of its berth the ladder it is desired to use, or for returning to its berth a ladder that has been used.

Figure 1 of the accompanying drawings shows a side elevation of a motor driven ladder truck constructed according to this invention. Fig. 2 shows a plan of the frame of this truck, looking down on the plane indicated by the dotted line 2-2 on Fig. 1. Fig. 3 shows on larger scale a view looking at the rear end of the truck with one of the ladder carriages moved out to the position occupied when a ladder is to be received or removed. Fig. 4 is a section on larger scale of one of the supporting arms and carriages on the plane indicated by the dotted line 4-4 on Fig. 3. Fig. 5 is a side view of one of the cross heads which are movable back and forth on the cross arms for moving the ladder carriages. Fig. 6 shows the bar that is used to operate the carriage moving means. Fig. 7 shows a side view with parts in sec-

tion of the ladder supports, the frame in this view being broken away and the supports being brought close together for the purpose of illustration. Fig. 8 shows a plan of the ladder supports in the same relation as shown in Fig. 7.

The frame 1, desirably formed of steel angle or channel beams, is mounted on springs 2 attached to the axles 3 that are supported by the wheels 4. The driver's seat 5 with the usual controlling lever 6 and steering wheel 7 are arranged at the front end of the frame above the housing 8 which incloses the motor. Along the sides of the frame are running boards 9 for carrying men and tools.

Standing upwardly at suitable distances apart along the middle of the frame are tubular metallic posts 10, 11, 12, 13. Fastened to the upright posts and extending outwardly on each side and transversely of the frame are ladder supporting cross arms 14, 15, 16. These cross arms are desirably made of steel angle plates or bars the lowest being the longest and the highest the shortest. There may be any desired number of central upright supporting posts and any desired number of outwardly extending cross arms on each post. In the apparatus illustrated there are four supporting posts with three ladder supporting cross arms on each, thus providing six independent berths which are open to each side so that six ladders of varying sizes may be carried by the truck, preferably the heaviest and longest being at the bottom, and these may be placed in their respective berths on the cross arms from each side, and may be taken out sidewise as it is desired to use them, without sliding them longitudinally or drawing them toward the rear of the truck.

The three rear posts at the top have cross arms 17. These cross arms support a deck 18 which has a seat 19 and rear steering wheel 20.

In order that the ladders 21 may be handled easily and quickly, when stored in the berths and when needed for use at a fire, ladder holding carriages 22 and 23 are arranged so as to be movable in and out along the ladder supporting cross arms. These carriages ride on rollers 24 that are held between the angle bars which make up the cross arms. The carriages on the same level on each side

are connected so that they will move together. At the outer ends the carriages on the same level are joined by a shaft 25 and at the inner ends they are joined by rods 26. 5 On each shaft 25 at the end of each carriage is a wing 27 that by rotating the shaft may be turned up so as to prevent a ladder from sliding off the carriage, or turned down to permit the easy removal of the ladder. Each 10 shaft 25 at its front end has a handle 28 for rotating it and turning the wings up or down. On each handle is a latch 29 that is adapted to engage notches in a sector 30 for holding the wings locked in the desired 15 position. At the inner end, in order to guide and hold it each carriage may have downwardly projecting arms 31. Each pair of these arms is connected by a bar 32 which when the carriage is moved out and tips down 20 will engage the under edges of the cross arm bars and thus prevent the carriage from dropping down too far. In order to insure easy action of the carriages when they tip, at the rear end of each there may be arranged upwardly extending spring plungers 25 33 which have rolls 34 that run in tracks 35 on the sides of the cross arms. The springs 36 of these plungers act as cushions for the rear ends of the carriages when they are 30 moved out and tipped down.

In the truck illustrated the carriages 23 on the cross arms which project from the intermediate supporting posts 11 and 12 are termed active carriages, as they are connected 35 with the operating mechanism, while the carriages 22 on the cross arms which project from the front and back supporting posts 10 and 13 are termed idle carriages as they are not directly connected with the operating 40 mechanism. The carriages 22 are connected with the carriages 23 as described by the shafts 25 and rods 26. Movable back and forth between the angle bars that make 45 up the cross arms which carry the active carriages 23 are cross heads 37. Each cross head has rolls 38 that run on the flanges of the bars between which the head travels. The cross heads are connected by links 39 with the outer ends of the active carriages.

50 Each of the top cross heads is connected by a link 40 with a lever 41 attached to the upper end of a shaft 42. Each of the middle cross heads is connected by a link 43 with a lever 44 that is attached to the upper end 55 of a tubular shaft 45. Each of the bottom cross heads is connected by a link 46 with a lever 47 that is attached to the upper end of a tubular shaft 48. These shafts are held vertical at the sides of the supporting posts 60 11 and 12, the solid shaft 42 extending through the tubular shaft 45 and the latter shaft extending through the tubular shaft 48. On the lower end of each of the tubular shafts 48 is a lever 49. On the lower end of 65 each of the tubular shafts 45 is a lever 50.

On the lower end of each of the solid shafts 45 is a lever 51. On each side of the center the levers 49 are connected by a bar 52 with a lever 53. This lever is connected by a link 54 on each side with a lever 55. The levers 50 on each side are connected by a bar 56 with a lever 57 that is connected by a link 58 with a lever 59. The levers 51 on each side are connected by a bar 60 with a lever 61 that is connected by a link 62 with a lever 63. The lever 55 on each side is fastened to the upper end of a solid shaft 64. The lever 59 on each side is fastened to a tubular shaft 65, and the levers 63 are fastened to a tubular shaft 66. These shafts extend vertically through bearings attached to the frame near the front end. On the lower end of each of the solid shafts 64 is a socket 67. On the lower end of the tubular shaft 65 is a socket 68. On the lower end of the tubular shaft 66 is a socket 69. The end of the bar 70 may be inserted in any one of these sockets and turned so as to move in or out the carriages holding the ladder which it is desired to handle. The lowest socket is connected by means of the levers and links with the lowest ladder carriages, the intermediate sockets are connected with the middle carriages, and the upper sockets are connected with the highest carriages, those on one side 75 manipulating the carriages on that side and those on the other side manipulating the carriages on that side. 80

With this truck a fireman or other person may insert a bar in the proper socket at the front end of the frame and turn it so as to move out a carriage and bring to one side the ladder placed thereon. When the carriages are brought out in this manner they tip down and the ladder can be easily and 100 quickly taken from them or allowed to slide from them when the wings are turned down. In order to restore a ladder the carriages in the proper berth are brought out and after the ladder is placed thereon and the wings 105 turned up to hold the ladder in place the carriages are returned to position by turning the bar which is applied to the proper socket at the front end of the frame. With this apparatus as it is not necessary to run the ladders in or out from the back end of the truck much time is saved in handling them and this is of great importance for in the emergencies of a conflagration it is necessary to save all the time possible. 110

115 The invention claimed is:

1. A ladder truck having a frame, supports extending upwardly along the center of the frame, cross arms projecting outwardly from said supports, ladder holding carriages movable in and out on the cross arms, and means for moving the carriages on the cross arms. 125

2. A ladder truck having a frame, supports extending upwardly along the center 130

- of the frame, cross arms projecting outwardly from said supports, ladder holding carriages movable in and out on the cross arms, and means arranged on one side of the frame for moving the ladder carriages on that side of the center supports, and means located on the other side of the frame for moving the ladder carriages on that other side.
5. A ladder truck having a frame, supports extending upwardly along the center of the frame, cross arms projecting outwardly from said supports, ladder holding carriages movable in and out on the cross arms, means for holding ladders on the carriages, and means for moving the carriages on the cross arms.
10. A ladder truck having a frame, supports extending upwardly along the center of the frame, cross arms projecting outwardly from said supports, the spaces between the cross arms being unobstructed so that ladders may be placed in or removed from said spaces without endwise movement, and means for carrying the ladders into and bringing them out of said spaces.
15. A ladder truck having a frame, supports extending upwardly along the center of the frame, cross arms projecting outwardly from said supports, ladder holding carriages movable in and out on the cross arms, and means for moving the carriages outwardly and causing them to tip down-wardly at the ends of the cross arms.
20. A ladder truck having a frame, supports extending upwardly along the center of the frame, cross arms projecting outwardly from said supports and providing unobstructed ladder berths, and means adapted to be operated near the front of the frame for removing each ladder independently from its berth on the cross arms.
25. A ladder truck having a frame, supports extending upwardly along the center of the frame, cross arms projecting outwardly from said supports, ladder holding carriages movable in and out on the cross arms, means for moving the carriages outwardly and causing them to tip down at the ends of the cross arms, and means at the ends of the carriages for locking the ladders thereon or releasing the ladders therefrom.
30. A ladder truck having a frame, supports extending upwardly along the center of the frame, cross arms projecting outwardly from said supports, ladder holding carriages movable in and out on the cross arms, and means for moving the carriages outwardly and causing them to tip down at the ends of the cross arms, and means at the ends of the carriages for locking the ladders thereon or releasing the ladders therefrom.
35. A ladder truck having a frame, supports extending upwardly along the center of the frame, cross arms projecting outwardly from said supports, ladder holding carriages movable in and out on the cross arms, means for moving the carriages outwardly and causing them to tip down at the ends of the cross arms, and means at the ends of the carriages for locking the ladders thereon or releasing the ladders therefrom.
40. A ladder truck having a frame, supports extending upwardly along the center of the frame, cross arms projecting outwardly from said supports, ladder holding carriages movable in and out on the cross arms, and means for moving the carriages outwardly and causing them to tip down at the ends of the cross arms, and means at the ends of the carriages for locking the ladders thereon or releasing the ladders therefrom.
45. A ladder truck having a frame, supports extending upwardly along the center of the frame, cross arms projecting outwardly from said supports, ladder holding carriages movable in and out on the cross arms, and means for moving the carriages outwardly and causing them to tip down at the ends of the cross arms, and means at the ends of the carriages for locking the ladders thereon or releasing the ladders therefrom.
